FLOOR CONSTRUCTION

Joseph G. Shryock, Philadelphia, Pa.

Application April 19, 1932, Serial No. 606,172

5 Claims. (Cl. 189—34)

My invention relates to flooring, and more particularly to the type of flooring adapted for use primarily in the construction of bridges and commercial buildings, although it may be readily used for other purposes and, in part, is a continuation of my co-pending application Serial No. 554,531, filed Aug. 1, 1931; for which Letters Patent 1,933,394 were issued October 31, 1933.

An object of my present invention is to provide a flooring which is not only exceedingly light but, at the same time, has great strength relative to its weight.

A further object of my invention is to provide a metallic flooring, the upper surface of which is covered with a substantially air and water-tight covering capable of maintaining its shape and original smooth surface under heavy and continual traffic loads.

A further object of my invention is to provide a flooring having the combined features of a strong and, as compared to its strength, relatively light sub-flooring, with a covering which may be readily taken up and replaced at necessary or desired positions and which after a few hours of traffic use will be indistinguishable from the portions which have not been repaired.

A further object of my invention is to provide a novel flooring which includes substantially rigid and strong sub-flooring which may be brought to the job in partially assembled condition, and which upon receiving the traffic contacting covering may be opened to traffic within a few hours after such covering is applied.

Other objects and advantages of my invention will be apparent from the following specification and from the drawing, illustrating one embodiment of my invention, in which:

Figure 1 is a perspective view of a portion of a floor, partly broken away, embodying the principles of my invention.

Fig. 2 is a vertical section through a portion of such flooring.

Fig. 3 is a similar sectional view illustrating a slightly modified construction within the scope of my invention, and

Figs. 4 and 5 are fragmentary sectional views illustrating details of my invention.

My invention comprises the use of a metallic sub-flooring structure such as that described in my pending application above referred to, the preferred form of which, illustrated in Fig. 1 of the accompanying drawing, comprises a plurality of light or junior channel members 5; adjacent channel members being arranged with their flanges 5^a in reversed meeting position, with the

edges of such adjacent flanges in contact with the web portions 5^b of adjacent channels. These channel members may be suitably connected together as here shown, by rivets 6, or bolts 7, passing through the abutting flanges, or such flanges 60 may be welded together in the manner set forth in my pending application. With the channel members arranged as thus described, a rigid sub-floor structure may be developed, consisting of channels in alternately reversed position forming 65 a sub-flooring having a series of troughs or channel portions between which are, preferably, webs of substantially the same width as the width of such channel portions. This sub-flooring structure may be carried in any suitable manner, as by 70 the beams 8, illustrated herein.

While, obviously, various types of traffic-bearing coverings may be applied to this sub-flooring, as pointed out in my pending application, I have conceived the idea of applying to such sub-flooring, a material known as asphalt bridge plank, and employing this material in a novel and highly advantageous manner. This traffic-bearing surface is well known to those skilled in the art, and comprises preformed members which I will herein- 75 after refer to as "boards"; composed primarily of fibrous material, which may include asbestos fibre, with a binder of an asphaltic material of such type as to hold the fibrous material in predetermined shape to which it is formed under high 80 pressure, while at the same time providing a certain amount of resilience due to the elastic qualities of the respective materials.

To form the traffic-bearing surface of my improved flooring, I position boards 9 within each of 90 the trough or channel portions of the metal sub-flooring so that they will form, with the web portions 5^b of the inverted channel members 5, a substantially level surface. These boards 9 are of such size relatively to the channel members 5 95 as to fill the space of the same so that no movement of these boards can take place transversely of the channels in which they are placed. In other words, the boards are of such size that they form a tight fit between the flanges 5^a of the 100 channel members 5. Provision may be made to prevent movement of the boards 9 longitudinally of the channels by the formation of projections 5^c in the web of the channel members receiving the same, which projections may be of any suitable 105 shape and may be formed either as indicated in Figs. 1 and 4 by pressing up a portion of the web 5^b, or by welding a small piece of metal to the web, as illustrated in Fig. 5. Suitable notches or recesses may be cut in the boards 9 at necessary 110

intervals to fit about or over the projections 5^c, and these notches or recesses preferably form a tight fit with the projections to prevent movement of the boards longitudinally of the channels.

5 I have found in practice that the provision of projections on the webs of the channel members fitting recesses in the boards is not essential if bolts or rivets having heads of sufficient size are used to connect the channel members, since 10 notches may be cut in the sides of the boards 9, to fit closely over the heads of the bolts or rivets, and thus the heads of the bolts or rivets may take the place of projections 5^c to prevent longitudinal movement of the boards.

15 Prior to positioning the boards 9 in place they and/or the channel members 5 may be coated with a suitable non-oxidizing cementitious material indicated at a, which not only aids in tying the boards to the channel members but also 20 serves as an air and water-tight coating and crack filler to maintain the upper surface of the channel members forming the sub-flooring entirely out of contact with moisture and the atmosphere. This cementitious material may be of an asphaltic nature, such for example as an asphalt emulsion.

Over the substantially level surface which is prepared as above described I place another layer 30 of boards 10, which may be of material similar to or identical with that of which the boards 9 are formed, and these boards 10 may be coated with cementitious material of the same character as that applied to the boards 9 so that they will adhere to the latter boards and to the portions of the inverted channel members whereby the latter 35 will be maintained out of contact with moisture and the atmosphere.

The boards 9 employed to fill the spaces between the flanges of the channel members and form a surface flush with the webs of the reversely placed channel members to receive the traffic-bearing surface comprising the boards 10, are materially thicker than the latter boards. In some instances it may be desirable to employ a plurality 40 of the boards 9 to fill the channel spaces, and in Fig. 3 I have shown two layers of these boards, indicated at 9^a. Thinner boards are capable of compression to a greater density, and with relatively deep channel portions or troughs a plurality 45 of the filler boards are preferably employed. For filling the channels and forming an even surface 50 upon which the traffic-bearing surface may be applied ordinary timber blocks may be used in place of the composite material with satisfactory results.

55 By the provision of a flooring such as above described I attain a structure which not only has all of the weight bearing and other features obtainable with the use of the metallic sub-flooring described in my pending application, but also 60 provides a means by which the use of the upper or traffic-bearing surface may be locked in place so that under traffic it will not spread or move. Such a traffic-bearing surface may be readily laid 65 and the floor so constructed is capable of use within a few hours after completion.

In repairing a floor of this type the individual 70 boards 10 may be taken up as units and others, previously coated with the cementitious material, immediately laid in their place. Such repaired places may be used by traffic immediately, and within a short period of time the new boards are 75 indistinguishable from those which formed the original portion of the flooring.

Obviously this structure is suitable not only for use as a flooring for bridges and other public and

highly traveled highways, but is suitable for use in commercial buildings; warehouses and manufacturing establishments, and all places where it is desirable to use a floor of light weight having a readily replaceable and heavy traffic-bearing surface.

Various modifications may be made in the above described embodiment of my invention without departing from the spirit and scope thereof as set forth in the following claims.

I claim:

1. A floor construction comprising a plurality of longitudinally flanged metallic channel members each composed of a web and flanges normal to said web; said flanges having beveled inner faces and said channel members being arranged with their adjacent flanges in interconnected relation, alternate members being disposed in reversed relationship whereby adjacent flanges of said associated members are brought into direct meeting relationship with their beveled surfaces in contact to form an inherently stable structure composed of alternately inverted trough sections, means for securing said metallic channel members together in fixed position, composition boards filling the space between the flanges of alternate members and extending to the level of the inverted trough sections, and a covering forming a replaceable wear surface overlying said composition boards and the portions of the metallic members in surface alignment therewith.

2. A floor construction comprising a plurality of longitudinally flanged metallic channel members, each composed of a web and flanges normal to said web; said flanges having beveled inner faces and said channel members being arranged with their adjacent flanges in interconnected relation, alternate members being disposed in reversed relationship whereby adjacent flanges of said associated members are brought into direct meeting relationship with their beveled surfaces in contact to form an inherently stable structure composed of alternately inverted trough sections, means for securing said metallic channel members together in fixed position, composition boards filling the space between the flanges of alternate members and extending to the level of the inverted trough sections, and a covering forming a replaceable wear surface overlying said composition boards and the portions of the metallic members in surface alignment therewith.

3. A floor construction comprising a plurality of longitudinally flanged metallic channel members, each composed of a web and flanges normal to said web; said flanges having beveled inner faces and said channel members being arranged with their adjacent flanges in interconnected relation, alternate members being disposed in reversed relationship whereby adjacent flanges of said associated members are brought into direct meeting relationship with their beveled surfaces in contact to form an inherently stable structure composed of alternately inverted trough sections, means for securing said metallic channel members together in fixed position, composition boards filling the space between the flanges of alternate members and extending to the level of the inverted trough sections, and a covering forming a replaceable wear surface overlying said composition boards and the portions of the metallic members in surface alignment therewith.
